(57) **CLAIM**

The ornamental design for an set of oral tobacco articles, substantially as shown and described.

DESCRIPTION

FIG. 1 is a perspective view of an set of oral tobacco articles; and,

FIG. 2 is top view of the set of oral tobacco articles of FIG. 1, the bottom view being a mirror image.

The broken lines which define environmental structure of the claimed design form no part thereof. The broken lines depict a container with the lid removed (i.e., upon opening by an adult tobacco consumer).
